(57) **CLAIM**

The ornamental design for an oral care package, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a perspective elevation view of an oral care package;

FIG. 2 is a front view thereof;

FIG. 3 is a right side view thereof;

FIG. 4 is a back view thereof;

FIG. 5 is a left side view thereof;

FIG. 6 is a top view thereof; and

FIG. 7 is a bottom view thereof.

FIG. 8 is a perspective elevation view of an oral care package;

FIG. 9 is a front view thereof;

FIG. 10 is a right side view thereof;

FIG. 11 is a back view thereof;

FIG. 12 is a left side view thereof;

FIG. 13 is a top view thereof; and

FIG. 14 is a bottom view thereof.

FIG. 15 is a perspective elevation view of an oral care package;

FIG. 16 is a front view thereof;

FIG. 17 is a right side view thereof;

FIG. 18 is a back view thereof; and

FIG. 19 is a left side view thereof;

FIG. 20 is a top view thereof; and

FIG. 21 is a bottom view thereof.

FIG. 22 is a perspective elevation view of an oral care package;

FIG. 23 is a front view thereof;

FIG. 24 is a right side view thereof;

(Continued)

FIG. 25 is a back view thereof;
 FIG. 26 is a left side view thereof;
 FIG. 27 is a top view thereof; and
 FIG. 28 is a bottom view thereof.
 FIG. 29 is a perspective elevation view of an oral care package;
 FIG. 30 is a front view thereof;
 FIG. 31 is a right side view thereof;
 FIG. 32 is a back view thereof;
 FIG. 33 is a left side view thereof;
 FIG. 34 is a top view thereof; and
 FIG. 35 is a bottom view thereof.
 FIG. 36 is a perspective elevation view of an oral care package;
 FIG. 37 is a front view thereof;
 FIG. 38 is a right side view thereof;
 FIG. 39 is a back view thereof;
 FIG. 40 is a left side view thereof;
 FIG. 41 is a top view thereof; and
 FIG. 42 is a bottom view thereof.
 FIG. 43 is a perspective elevation view of an oral care package;
 FIG. 44 is a front view thereof;
 FIG. 45 is a right side view thereof;
 FIG. 46 is a back view thereof;
 FIG. 47 is a left side view thereof;
 FIG. 48 is a top view thereof; and
 FIG. 49 is a bottom view thereof.
 FIG. 50 is a perspective elevation view of an oral care package;
 FIG. 51 is a front view thereof;
 FIG. 52 is a right side view thereof;
 FIG. 53 is a back view thereof;
 FIG. 54 is a left side view thereof;
 FIG. 55 is a top view thereof; and
 FIG. 56 is a bottom view thereof.
 FIG. 57 is a perspective elevation view of an oral care package;
 FIG. 58 is a front view thereof;
 FIG. 59 is a right side view thereof;
 FIG. 60 is a back view thereof;
 FIG. 61 is a left side view thereof;
 FIG. 62 is a top view thereof; and
 FIG. 63 is a bottom view thereof.
 FIG. 64 is a perspective elevation view of an oral care package;
 FIG. 65 is a front view thereof;
 FIG. 66 is a right side view thereof;
 FIG. 67 is a back view thereof;
 FIG. 68 is a left side view thereof;
 FIG. 69 is a top view thereof; and,
 FIG. 70 is a bottom view thereof.

In the drawings, the evenly spaced broken lines show portions of an oral care package that form no part of the claim; the dash-dot-dash broken lines represent boundaries of the claimed design and form no part thereof.
